(57) **CLAIM**

The ornamental design for a power supply for portable electronic device, as shown and described.

DESCRIPTION

FIG. 1 is a perspective view of a power supply for portable electric device, showing our new design.

FIG. 2 is a top view of the power supply of FIG. 1.

FIG. 3 is a bottom view of the power supply of FIG. 1.

FIG. 4 is a front view of the power supply of FIG. 1.

FIG. 5 is a rear view of the power supply of FIG. 1.

FIG. 6 is a right side view of the power supply of FIG. 1; and,

FIG. 7 is a left side view of the power supply of FIG. 1. The broken lines showing are for illustrative purposes and form no part of the claimed design.
